United States Patent Office.

JOHN F. MILLIGAN, OF ST. LOUIS, MISSOURI, ASSIGNOR TO HIMSELF AND
J. W. BRANCH, OF SAME PLACE.

Letters Patent No. 69,113, dated September 24, 1867.

IMPROVEMENT IN COTTON-BALE TIE.

The Schedule referred to in these Letters Patent and making part of the same.

TO ALL WHOM IT MAY CONCERN:

Be it known that I, JOHN F. MILLIGAN, of the city and county of St. Louis, and State of Missouri, have invented a new and useful Improvement in Ties for Baling-Bands; and I do hereby declare that the following is a full and clear description thereof, reference being had to the accompanying drawings, and to the letters of reference marked thereon.

This invention relates to a metallic tie-piece, the opposite ends of which are placed in parallel planes, the top face of one end and the bottom face of the other end being located in nearly or quite the same plane indicated in the sectional drawings by the line $x\ x$. Each end of the tie-piece is pierced with a mortise for the reception of the end of the baling-band.

To enable those skilled in the art to make and use my improved tie, I will proceed to describe its construction and operation.

Figure 1 of the drawings is a perspective view of one of the improved ties as it appears when in the position of securing the two band ends together.

Figure 2 is a plan of the tie-piece.

Figure 3 is a section of the same, taken on the line $y\ y$ of fig. 2.

Figure 4 is a sectional elevation of the tie and portions of the band ends as they appear while in the act of coupling.

The tie-piece A A' has two mortises $a\ a^1$ for the reception of the band ends B B', the first of which is to be entered through its mortise and doubled back around the end rail of the tie-piece and secured in place by riveting, or otherwise, as may be preferred, preparatory to the application of the band to the bale. The end B' is then to be inserted through its mortise in the manner shown in fig. 4; the tie-piece being turned up partly on one edge to facilitate the entrance, after which, when the press is released from the bale, the expanding force of the said bale will press the end B' into a sharp bend across the lower corner of the central rail of the tie-piece and the upper corner of the end rail, thus making this form of a tie a self-acting one, readily adaptable to any portion of the band, the whole strength of which may be obtained, as there are no perforations of the attachment of the tie-piece. The formation of the tie-piece, with its two ends A A' connected together at the central rail a^2 in such a manner that said ends are placed in parallel planes with the line $x\ x$, which bisects the tie-piece, falling nearly or quite in the bottom surface of A and the top surface of A', is the chief improvement in this form of tie, as such construction permits an easy entrance for the end B' of the band, and securely binds it across the corners of the rails forming the mortise a^1 , when once it is in place on the bale.

I am aware that ties of similar shape have been shown in the reissued Letters Patent to James Speer, dated February 19, 1867, in which a buckle is shown, the bend whereof is in a direct line of the mortises, thus permitting the ends of a band to be simply hooked to the bearing on the central rail of the clasp, but in nowise securing the tie against end thrust. Now, it will be observed that the form by me described is substantially that of two single mortise tie-plates placed with the ends overtopping, thus forming a central rail a^2 of double thickness of any other part. In the action of my said tie the band end B is as shown permanently secured, but the end B' is passed on the upper face of the part A' downwardly and under the central rail, and thereupon, by the force of the compressed material under the band, this end is forced upward past the edge of a^2 and then lies closely under B. Thus the end B' receives a double bend or kink, which prevents the same from moving either under longitudinal thrust or push, and thus I have formed a more secure and improved tie.

Having thus fully described my invention, what I claim is—

The tie-piece formed of the parts A and A', having the mortises a and a^1 respectively, and being joined by a central rail, a^2 , in the manner set forth; when combined with and acting upon the band ends B and B', substantially as and for the purpose described.

In testimony of which invention I hereunto set my hand and seal in presence of—

JOHN F. MILLIGAN. [L. S.]
